(57) **CLAIM**

I claim the ornamental design for a bird feeder, as shown and described.

DESCRIPTION

FIG. 1 is a perspective view of a first embodiment of a bird feeder according to the present design;

FIG. 2 is a front elevation view thereof, the rear view being a mirror image, except for the clip shown on the base thereof;

FIG. 3 is a side elevation view thereof, the opposite side being a mirror image, except for the clip shown on the base thereof;

FIG. 4 is a perspective view of a second embodiment of the bird feeder of FIG. 1;

FIG. 5 is a front elevation view thereof, the rear view being a mirror image, except for the clip shown on the base thereof;

FIG. 6 is a side elevation view thereof, the opposite side being a mirror image, except for the clip shown on the base thereof;

FIG. 7 is a perspective view of a third embodiment of the bird feeder of FIG. 1;

FIG. 8 is a front elevation view thereof, the opposite side being a mirror image, except for the clip shown on the base thereof;

FIG. 9 is a side elevation view thereof, the opposite side being a mirror image, except for the clip shown on the base thereof;

FIG. 10 is a top view of the bird feeder embodiment shown in FIG. 1;

FIG. 11 is a bottom view of the bird feeder embodiment shown in FIG. 1;

FIG. 12 is a top view of the bird feeder for both the second and third embodiments shown in FIGS. 4 and 7; and,

FIG. 13 is a bottom view of the bird feeder for both the second and third embodiments shown in FIGS. 4 and 7.

The broken lines shown in the figures are for illustrative purposes only and form no part of the claimed design.
